JAMES W. TEFFT, OF BUFFALO, NEW YORK.

Letters Patent No. 91,579, dated June 22, 1869.

IMPROVED SLIDE FOR EXTENSION-TABLES.

The Schedule referred to in these Letters Patent and making part of the same.

To all whom it may concern:

Be it known that I, JAMES W. TEFFT, of the city of Buffalo, in the county of Erie, and State of New York, have invented certain new and useful Improvements in Slides for Extension-Tables; and I do hereby declare that the following is a full, clear, and exact description of the same, reference being had to the annexed drawing, which forms a part of this specification.

My invention relates to providing an extension-table with a pair or more wooden or metal bars, each provided with two grooves, meeting upon the lateral surface of the bar, the one inclined downward and inward at an angle of forty-five degrees, more or less, the other upward and inward at the same angle.

These grooves are cut or sawed in the lateral surface of the bar, and from the central line thereof, and have such line as a common point of divergence, the grooves in each bar being in the same relative position, and only the surfaces touching are grooved.

In the case of two bars being used, the groove of one is provided at one end with a double diagonal cross of metal or other suitable material firmly set in the groove, and of such size that the arms of the cross will fit and slide smoothly in the grooves of the adjacent bar, and so arranged that one-half of the cross laterally projects above the lateral surface of the bar.

At a proper distance from said cross, and embedded in said groove, is a stop, similar in form to a section of said cross when bisected laterally, and is secured in such position by means of a pin, so driven as not to project above the surface of the stop.

At the other end of the bar a similar stop is set in the groove, and secured in like manner.

The adjacent bar is provided with a groove similar in all respects to that of the former-described bar, which groove is provided at one end with a device consisting of a double diagonal cross, and a section of such cross bisected laterally, united in one piece, having the stop and lower part of the double cross embedded in the groove, and secured by a pin, at a point opposite the end of the first-described groove, at the point where the stop is fixed therein. The pin securing said device is so arranged as not to project above its surface.

It is evident from the above that any number of bars may be used in combination.

In order to enable others to make and use my invention, I will proceed to describe its construction and illustrate its operation.

The following is a description of the drawings:

Figure 1 represents the lateral surfaces of two adjacent bars, A and B.

Figure 2 represents the end of the same, when attached.

Figure 3 represents an end view of the bar A.

Figure 4 represents the stop c, which is similar to the stop c'.

Figure 5 represents the double diagonal cross.

Figure 6 represents the double diagonal cross t, in combination with the section of such cross, bisected laterally.

The operation of attaching the bars and using the invention is described as follows:

Remove the stop c at the point z by drawing the pin v in the bar B; superpose the bar A in such manner as that the grooves come exactly opposite each other; slide the bar A, thus placed towards the cross d, in such manner as to cause the cross of the device z to fit into the groove m, then slide the bar A towards the stop c', at the point s, replace and affix the stop c. At the point z insert the pin v. The attachment is thus complete, and any number of bars may be thus joined.

The cross d operates as a slide, moving in the grooves m, and also as a means of attachment to hold the bars together.

This is due to its peculiar construction, and its fitting in the grooves m, and being embedded and secured in the groove n.

The combined cross and stop z operates similarly as to the cross t thereof, but performs the additional function of a stop by the part t; and by its formation, having but a bisected lateral section, w, at one end, admits of the bars being so placed as to receive the crosses into the grooves.

The stop c, at the point z, prevents the bars separating or from extending in wrong direction.

The stop c, at the point s, serves to regulate the length of the extension, which, in fig. 1, is shown by the distance between the red lines o and p.

The pin v, as used in securing the stops, cross, and combined cross and stop, is so formed and driven as to present no impediment to the surface passing over it.

It is well known that double crosses and grooves have been used by others, and I do not claim them in this application; but

What I do claim as my invention, and desire to secure by Letters Patent, is—

The stops c and c', in combination with the cross and stop z, and the double cross d, and the pin v, arranged and used substantially as described.
